DESIGN FOR A JAR

Charles R. Tips, Three Rivers, Tex.

Application October 17, 1935, Serial No. 59,090

Term of patent 14 years

To all whom it may concern:

Be it known that I, Charles R. Tips, a citizen of the United States, residing at Three Rivers, in the county of Live Oak, State of Texas, have invented a new, original, and ornamental Design for a Jar, of which the following is a specification, reference being had to the accompanying drawing, forming part thereof.

new design, the opposite face being substantially the same as that shown.

Figure 2 is a side elevational view, the other side being substantially the same as the side shown.

I claim:

The ornamental design for a jar, as shown and described.

CHARLES R. TIPS.
